CIRCULARLY POLARIZED OMNIDIRECTIONAL CONE MOUNTED SPIRAL ANTENNA
John D. Dyson and Paul E. Mayes, Champaign, Ill., assignors to The University of Illinois Foundation, a non-profit organization of Illinois
Filed Dec. 29, 1960, Ser. No. 79,432
10 Claims. (Cl. 343—895)

This invention relates to antennas and, more particularly, it relates to antennas having conical beam or omnidirectional radiation patterns that are essentially independent of frequency over wide bandwidths.

It is known that if the shape of an antenna were such that it could be specified entirely by angles, the antenna would make an ideal broadband radiator, since its operation would be theoretically independent of frequency. All antennas which meet this criterion, however, are infinite in extent, so that it is necessary to specify at least one length for an antenna of finite size. By making this one length very large compared with the wavelength of operation of a given antenna, it is possible in some cases to achieve antenna performance which is practically independent of wavelength over wide bandwidths.

An antenna which can be made to have a very wide band of operations in which performance is independent of wavelength is the balanced equiangular spiral antenna. The one specified length for this antenna, the arm length, need not be large compared to a wavelength, and in fact need only be comparable to a wavelength at the lowest frequency of operation to obtain performance essentially independent of frequency. This antenna comprises two coplanar spiral arms, each arm being defined by two identical equiangular spiral curves, one rotated through a fixed angle around the origin (i.e., the central point of the antenna) with respect to the other. The arms themselves are also identical in shape, one being rotated through an angle of about 180° from the position of the other. Planar antennas of this type have broadband bidirectional radiation patterns extending perpendicularly to the plane of the antenna.

As described in Dyson U.S. Patent 2,958,081, issued on February 11, 1960, the balanced equiangular spiral antennas described above can be modified to exhibit unidirectional radiation patterns while maintaining the broad bandwidths which such antennas possess. The unidirectional radiation patterns are achieved by wrapping a planar balanced equiangular spiral antenna on the surface of a cone and feeding the antenna at the apex thereof by a feed cable carried along one arm. Such antennas exhibit substantially symmetric radiation patterns having a maximum on the antenna axis off the apex of the cone.

In accordance with the invention it has been found that it is possible to obtain a conical beam mode of operation from the balanced conical antenna by constructing the antenna with an even number of arms more than two and connecting these arms to provide a suppression of the radiated fields on the axis of the antenna. The construction of the antennas of the invention will be better understood from the following detailed description thereof taken in conjunction with the accompanying diagrams in which:

FIGURE 1 is a plan view of an antenna embodying the features of the invention;

FIGURE 2 is an enlarged detail of the apex of the antenna shown in FIGURE 1;

FIGURE 3 is an enlarged detail looking down on the apex of the antenna of FIGURE 1;

FIGURE 4 is a sketch of the coordinate system used in obtaining radiation patterns for the antennas of the invention; and

2

FIGURES 5(a), 5(b), and 5(c) are typical radiation patterns of the electric fields in the planes indicated.

FIGURE 1 depicts a typical embodiment of the invention comprising four spiraling arms 11, 12, 13, and 14 which are wound on the surface of an electrically non-conductive cone 16. As shown in FIGURE 2, a small portion of the cone near the apex is truncated, since it would be physically impossible to construct this portion of the antenna because of the extremely small size of the arms in this region.

FIGURE 3, a top view of a portion of the antenna of FIGURE 1, shows a projection thereof on a plane surface. In such a projection each of the arms of the antenna is defined by an equiangular (or logarithmic) spiral. An equiangular spiral is a plane curve which may be defined by the equation:

$$\rho = ke^{a\phi}$$

or

$$a\phi = \ln \frac{\rho}{k}$$

where ρ and ϕ are the conventional polar coordinates and a and k are positive constants.

The equiangular spiral curve derives its name from one of its properties, namely, the fact that the angle (designated α) formed by a radius vector and a tangent to the curve at the point of intersection with the radius vector, is always constant. The value of α can be determined from the relationship

$$\tan \alpha = \frac{1}{a}$$

The constant a thus determines the rate of spiral of the curve and the constant k determines the physical starting point of the curve when $\phi=0$, as will be apparent to those skilled in the art.

Considering the plane curves partially shown in FIGURE 3 (that is, the projection of a portion of the outlines of the arms of the actual antenna), the outer and inner edges of every arm are defined by the same curve which is rotated about the origin or central point of the figure. Thus, for example, consider the outer edge of arm 11. This curve can be represented by an equation of the form

$$\rho_1 = ke^{a\phi}$$

The inner edge of arm 11 is actually the same curve as that defining the outer edge, except that it has been displaced about the origin through an angle δ . The equation of the inner edge of arm 11 may therefore be represented by

$$\rho_2 = ke^{a(\phi-\delta)} = K\rho_1$$

where

$$K = e^{-a\delta}$$

In a similar manner the curves defining arms 12, 13, and 14 are identical with those defining arm 11 but have been rotated through consecutive angles of 90° ($\pi/2$ radians) and thus have the equations

$$\rho_3 = ke^{a\left(\phi-\frac{\pi}{2}\right)}$$

for the outer edge of arm 12 and

$$\rho_4 = ke^{a\left(\phi-\frac{\pi}{2}-\delta\right)}$$

for the inner edge of arm 12,

$$\rho_5 = ke^{a(\phi-\pi)}$$

for the outer edge of arm 13 and

$$\rho_6 = ke^{a(\phi-\pi-b)} = K\rho_5$$

for the inner edge of arm 13, etc.

The curves defining the edges of the arms of the antenna shown in FIGURE 1 can be described by equations similar to those used for the planar version thereof, with the introduction of an additional variable, the cone angle ψ . The radial distance along the surface of the cone (extended if required) from the vertex to the outer edge of one arm (e.g., 11) is given by the equation

$$\rho_1 = ke^{\left(a \sin \frac{\psi}{2}\right)\phi} = ke^{b\phi}$$

where

$$b = a \sin \frac{\psi}{2}$$

and ψ is the included cone angle.

The inner edge of arm 11 is defined by

$$\rho_2 = ke^{b(\phi-b)} = K'\rho_1$$

where

$$K' = e^{-b\delta}$$

The edges of the other arms (e.g. 12) can be defined by the equations of the same type:

$$\rho_3 = \rho_1 e^{-b\frac{\pi}{2}}$$

(outer edge of arm 12) and

$$\rho_4 = K'\rho_3$$

(inner edge of arm 12), etc.

It can be seen that for an included cone angle ψ , of 180° (i.e., the planar form of the antenna) the above equations reduced to the form

$$\rho_1 = Ke^{a\phi}, \rho_2 = K\rho_1$$

etc. as previously described.

In contrast to the balanced two-arm version in which the arms are fed 180° out of phase, with the antennas of the invention the number of choices of feeding systems increases. In general, the antenna can be fed in any symmetrical manner which provides a suppression of the radiated fields on the axis of the antenna. For example, with a four-arm antenna this can be achieved by connecting opposite arms together and feeding one pair against the other, i.e., 180° out of phase. Such a system is shown in FIGURES 2 and 3, which show a coaxial feed cable 17 bonded to arm 11, with center conductor 18 of the cable connected to cable 19 which is joined to both of arms 12 and 14. As shown in FIGURE 2, the outer conductor of cable 17 extends to arm 13 and electrically joins this arm with arm 11. Balance and symmetry of this feed system are important if symmetrical patterns are desired. For this reason each of the arms is provided with a dummy coaxial cable for preserving physical symmetry. As an alternative to this method of feeding, the antenna can be fed by a balanced feed line, or a coaxial line and balun, placed on the axis of symmetry.

The four-arm antenna can also be fed in accordance with the invention by exciting the two pairs of arms with a 90° phase shift between them. Thus, for example, if arm 11 of FIGURE 3 is used as a datum, suppression of radiation along the antenna axis will be obtained if the excitations to the arms have the following phase relationships:

Arm 11	0°
Arm 14	-90°
Arm 13	-180°
Arm 12	-270°

Antennas having more than 4, e.g., 6 arms, can be excited in methods similar to those described above. In

one method a uniform delay is introduced progressively between adjacent arms amounting to 60° for a six-arm antenna. (In the general case of an antenna having n arms, the phase change between successive arms would be

$$\frac{360^\circ}{n}$$

where n is the number of arms.) Thus if one arm is taken as the datum and assuming that the arms spiral outwardly in a clockwise direction when viewed from the top or apex of the cone, successive arms proceeding in a counter clockwise direction would have the phase relationships: 0°, -60°, -120°, -180°, -240°, -300°. If the arms spiraled in the opposite direction to that assumed, the relative phase shift would also be reversed and applied to the arms in a clockwise direction.

In another suitable method for feeding an antenna of the invention, the phase shifts 180° between arms. In this case, for a six-arm antenna successive arms would have the phase relationships: 0°, -180°, 0°, -180°, 0°, -180°. This manner of feeding also can be applied generally to an antenna having any even number of arms.

Although in general antennas of the invention with only four arms will be satisfactory for many practical purposes, a greater number of arms can be used to provide more uniform pattern and far field phase characteristics as a function of the azimuthal angle ϕ (FIGURE 4).

As shown in FIGURE 4, the antennas of the invention do not radiate in an axial direction, so that the radiation pattern is conical in shape. By suitable selection of the antenna parameters, particularly the angle α governing the rate of spiral, the angle of orientation of the maximum radiation off the axis of the antenna can be made to assume values over a wide range. Thus, for example, the angle of orientation θ of the beam maximum can be varied through the range from about 40° to more than 90° by varying α from about 75° to about 45°, for cones having a cone angle ψ of about 15-20°. When the beam maximum is located at $\theta=90^\circ$, the antenna constitutes a simple, very broad band, circularly polarized, omnidirectional radiation source.

The arms of the antenna are made of an electrically conducting material, suitably sheet copper, aluminum, or the like. The antennas can be constructed in any suitable manner. A preferred method is by drawing the outline of the arms on the development of the cone, which drawing is then transferred by a silk screen process to a thin copper-clad Teflon impregnated glass cloth. After forming the arms by etching away the undesired portions of the copper cladding, the base material is formed into a cone and the arms are soldered along the joint. The cone thus formed can be supported by any of the well-known materials which are efficient insulators at high frequencies, such as polystyrene. Since the cone of insulating material is not an essential part of the antenna and is used only to support the arms, it can be eliminated if the arms are made of a rigid material, such as a sheet of copper strong enough to support its own weight.

The upper frequency limit of the band of operation for the antennas of the invention is determined by the fineness of the construction of the spiral at the feed point, i.e., at the vertex of the cone. Since equiangular spiral curves converge to a point as a limit at the origin, it is necessary in a practical structure to terminate the central portion in a small straight or tapered section. The upper cut-off frequency of the antenna is the frequency at which the truncated apex of the cone becomes approximately $\frac{1}{4}$ wave-length in diameter. As an example, for a termination of the apex at a 1-inch diameter the upper frequency limit is approximately 3000-4000 mc.

The operating bandwidth is at the control of the designer. The low frequency limits are effected by the length and the width of the arms of the antennas and hence the diameter of the base of the cone, and are independent of the upper frequency limit. Thus, for example,

the low frequency limit can be lowered by increasing the arm length and/or by increasing the width of the arms as in the case of the balanced two-arm conical antennas.

Although in the preferred form the antennas of the invention have arms each edge of which is defined by an equiangular spiral, so that the width of each arm constantly increases at increasing distances from the apex of the cone, it is also possible to construct practical antennas having advantageously wide bandwidths in which the width of the arm is constant or essentially constant. Thus, for example, antennas in which the arms consist of coaxial cables alone, arranged to follow equiangular spiral paths, may have acceptable patterns, particularly if α is large, e.g., 60° or more. These "wire" versions of the antenna can most conveniently be constructed from rigid wall coaxial cable and are advantageous for use at the UHF and VHF frequencies.

It is also possible to construct practical antennas having advantageously wide bandwidths in which the arms are constructed to follow an Archimedes spiral, which is defined by the equation

$$\rho = a\phi$$

Although these antennas are not frequency independent, they also produce conical beam or omnidirectional patterns with the excitations previously described. For antennas based on the Archimedes spiral the angle between the axis of the antenna and the maximum of radiation varies with the frequency of operation.

The practical results which are obtainable with the antennas of the invention are demonstrated by a four arm antenna constructed on a 15° cone with a diameter of 31 cm. at its base and further defined by the parameters $\alpha=45^\circ$ and $K=0.925$. This antenna was etched from flexible, copper-clad, Teflon-impregnated, fiberglass material and then formed into a cone. The feed cable was RG141/U. The energized cable was carried along one arm; dummy cables were on the other arms to maintain structural symmetry. Typical radiation patterns of this antenna are shown in FIGURE 5 for a frequency of 1200 mc. The patterns shown are for E_θ and E_ϕ polarized fields. FIGURES 5(a) and 5(b) are pattern cuts through the axis of the antenna at right angles to each other; FIGURE 5(c) is for a cut perpendicular to the axis, on the $\theta=90^\circ$ plane.

Antennas in accordance with the invention can be made to have bandwidths of 10 to 20 or more to 1 over which the radiation patterns and input impedance are essentially constant. In order to obtain the maximum bandwidth, however, it should be noted that these are balanced antennas and a balanced feed is necessary for optimum performance. The feed may be brought in along the axis of the antenna by using a balanced feed line or by an unbalanced line and balancing transformer or balun. The bandwidth of this latter method, of course, depends upon the bandwidth of the balun. The rapid decay of the current along the arms, however, makes possible the previously mentioned highly useful method of feeding the balanced antenna with an unbalanced transmission line. Since the ends of the antenna arms do not carry appreciable antenna currents except at the very lowest frequency of operation, the arms themselves act as an "infinite balun," the feed terminals are isolated from ground in a balanced manner and the outside of the feed cable beyond the antenna arms does not carry a significant amount of antenna current. However, as the frequency of operation is decreased a point will be reached where the presence

and location of this cable alters the radiation pattern. This frequency, however, is below that at which the antenna should be expected to operate satisfactorily. In order to compensate for the presence of the feed cable 5 insofar as possible, a dummy cable may be placed on the other arm to maintain physical symmetry.

The input impedance of the antennas of the invention remains relatively constant over a wider frequency range than the usable pattern bandwidth.

The foregoing detailed description has been given for clearness of understanding only, and no unnecessary limitations should be understood therefrom, as modifications will be obvious to those skilled in the art.

What is claimed is:

15. 1. A broadband antenna comprising an even number greater than 2 of substantially identical electrically conducting elements wound so as to lie on a conical surface having an included cone apex angle in the range between approximately 15° and 20°, at least one of said elements being electrically insulated from the remainder, each of said elements having at least one edge which projected on a plane perpendicular to the axis of said conical surface is substantially in the form of a spiral, said elements being symmetrically placed about the axis of said conical surface.
20. 2. The antenna of claim 1 wherein said spiral is an equiangular spiral.
25. 3. The antenna of claim 1 wherein the number of said arms is 4.
30. 4. The antenna of claim 1 which is fed at the apex by a feed cable which is carried on one of said elements.
35. 5. The antenna of claim 4 in which a dummy feed cable is carried by each of said other elements.
40. 6. A broadband antenna comprising an even number greater than 2 of substantially identical electrically conducting elements wound so as to lie on a conical surface having an included cone apex angle in the range between approximately 15° and 20°, at least one of said elements being electrically insulated from the remainder, each of said elements being defined by a pair of curves which when projected on a plane perpendicular to the axis of said conical surface have the form of equiangular spirals, said elements being symmetrically placed about the axis of said conical surface.
45. 7. The antenna of claim 6 which is formed of thin electrically conducting sheet material.
50. 8. The antenna of claim 6 wherein the number of said arms is 4.
55. 9. The antenna of claim 6 which is fed at the apex by a feed cable which is carried on one of said elements.
60. 10. The antenna of claim 9 in which a dummy feed cable is carried by each of said other elements.
